UNITED STATES PATENT OFFICE.

THOMAS NOWELL AND GEORGE H. WILSON, OF VILONIA, ARKANSAS.

MOLE-PLOW.

SPECIFICATION forming part of Letters Patent No. 376,674, dated January 17, 1888.

Application filed November 7, 1887. Serial No. 254,540. (No model.)

To all whom it may concern:

Be it known that we, THOMAS NOWELL and GEORGE H. WILSON, citizens of the United States, residing at Vilonia, county of Faulkner, and State of Arkansas, have invented certain new and useful Improvements in Mole-Plows, of which the following is a specification.

Our invention relates to that class of plows employed for draining wet lands by forming a sub-drain or duct without disturbing the surface of the soil; and it has for its object certain features of novelty in the construction of such implements, which will be first described, with reference to the accompanying drawings, and then more specifically pointed out in the claims.

In said drawings, Figure 1 is a side elevation of a mole-plow provided with our improvements. Fig. 2 is a top view of the same.

In our invention the standard 1, to which the mole 2 is secured, is made very thin, and has its forward edge sharpened, in order that the implement may be used on lawns or other sodded grounds without marring the surface of the lawn by tearing ragged furrows through the sod and in order to make the traction of the implement more easy. This standard 1 is inserted in a vertical slot, 3, which is considerably longer than the width of the standard, for the purpose of permitting the adjustment of the latter.

On the top of the beam is a metal or other suitable plate, 4, which is bolted or secured in any desirable manner to the beam, and has a slot, 5, which fits the standard 1 exactly. This slot is located midway between the ends of the slot 3, so as to permit the mole to oscillate either backward or forward for the purpose of adjustment.

On the under side of the beam and directly against the standard 1 is a block, 6. Looped around the standard is a metal or other strap, 7, which passes under the block 6, and passes diagonally upward through the beam and plate, and has its upper end screw-threaded, by means of which it is secured to the plate by a nut, 8. It will be seen that by tightening this nut the standard will be drawn against the block and the block pushed upward against the beam, thus binding the standard rigidly in its place.

At the forward end of the beam we provide a wheel, 9, for the usual purpose.

Having thus described our invention, the following is what we claim as new therein and desire to secure by Letters Patent:

The combination of the beam having an oblique perforation and a vertical and downwardly-flaring slot, a plate secured to the top of said beam and having a perforation and a slot corresponding, respectively, with the said oblique perforation and slot in the beam, a colter passing through the slot in said beam and plate and carrying a mole at its lower end, a metallic strap looped around said colter, passing through the oblique perforation in said beam, and having its end screw-threaded, a three-cornered block interposed between said colter-strap and beam, and a nut on said strap for binding the colter in position, essentially as set forth.

THOMAS NOWELL.
GEORGE H. WILSON.
